HEEL END LASTING MACHINES

Edward Quinn, Saugus, and Paul W. Senfleben, Beverly, Mass., and Ernest W. Stacey, deceased, late of Beverly, Mass., by Helen M. Stacey, executrix, Beverly, Mass., assignors to United Shoe Machinery Corporation, Flemington, N. J., a corporation of New Jersey

Application November 18, 1953, Serial No. 392,832

23 Claims. (Cl. 12—12.3)

This invention relates to machines for shaping shoe uppers over lasts, and is herein illustrated in its application to machines for lasting end portions of shoe uppers.

It is an object of the present invention to provide an improved end lasting machine of the type employing pressure fluid operated means for actuating the lasting wipers. It is a further object of the invention to provide a hydraulic actuating mechanism for the lasting wipers of a machine for lasting end portions of shoe uppers characterized by the construction and arrangement of the wipers and their carriers whereby the wipers come to rest at the end of the machine cycle separated from each other to provide clearance for the operation of instrumentalities which position and prepare the shoe upper parts for the subsequent operation of the wipers.

With the above objects in view the invention, in one aspect thereof, consists in the combination with the end lasting wipers of a lasting machine of a first piston, means operated by the first piston for imparting advancing movements of translation to the wipers, means for guiding the advancing movements of translation of the wipers in convergent paths, a second piston, and means operated by the second piston for imparting to the wipers angular movement relatively to each other to wipe the lasting margin of a shoe upper inwardly over an insole on a last bottom. In the illustrated organization the first piston acts on a pair of wiper carriers which mount the wipers respectively for angular movement relatively to the carriers and the second piston operates to impart to the wipers angular movement relatively to the carriers. In another aspect of the invention the cylinder in which the second piston operates is constructed and arranged to advance with the wiper carriers during the operation of the first piston in order to maintain the angular disposition of the wipers relatively to each other during the advancement of the carriers to bring the wipers into wiping position.

For assisting the operation of the pressure fluid operated means for advancing the wiper carriers the illustrated machine is provided with a booster which, as herein illustrated, operates during the advancement of the wiper carriers to urge the carriers toward each other in order to assist the movement of the wipers into a mutually articulated position from a position in which the wipers are separated from each other.

In order to insure the application of adequate wiping pressure by the wipers to the lasting margin of the upper the present invention, in another aspect thereof, consists in the combination with the wipers and their carriers of a holdown constructed and arranged to hold the wiper and carrier assemblies against movement in one direction widthwise of a shoe in the machine.

In order to provide for the movement of the wipers from their rest position in which they are separated from each other into their mutually articulated position preparatory to the wiping operation the support for the free end portion of each of the wiper carriers is combined with a cam means for determining the path of move-

2

ment of the free end portion of the carrier relatively to the support during the advancement of the carrier.

Inasmuch as the wiper assemblies include in their organization means for driving fastenings for securing the upper in lasted position, the present invention provides means, herein illustrated as an abutment member, for determining the overwiped position of the wipers. In order to provide for variations in the overwiped position of the wipers in accordance with shoe sizes, means is provided for adjusting the abutment member lengthwise of a shoe in the machine. Inasmuch as it is desirable to adjust the overwiped position of the wipers in accordance with variations in shoe widths as well as variations in shoe sizes, the present invention contemplates two separate adjusting means for the above member. In the illustrated organization this is achieved by mounting the abutment member on a slide and providing means for adjusting the slide lengthwise of a shoe in the machine and means for adjusting the abutment member relatively to the slide lengthwise of the shoe.

These and other features of the invention will now be described with reference to the accompanying drawings and pointed out in the appended claims.

In the drawings,
25 Fig. 1 is a plan view illustrating the heel end lasting organization of a machine embodying the features of the present invention, certain parts being broken away to permit the showing of underlying parts;

20 Fig. 2 is a front elevation of the mechanism illustrated in Fig. 1;

25 Fig. 3 is a right side elevation;

Fig. 4 is a plan view showing the lasting wiper organization in a position different from that shown in Fig. 1, the left wiper assembly being shown in section on the line IV—IV of Fig. 2;

30 Fig. 5 is a plan view of the wiper assembly showing the wipers at the limit of their overwiping movements, the left side of the holdown plate being broken away;

35 Fig. 6 is an enlarged view in section on the line VI—VI of Fig. 4;

30 Fig. 7 is an enlarged view partly in section on the line VII—VII of Fig. 5 illustrating mechanism for adjusting an abutment member which determines the limit of the overwiping movement; and

45 Fig. 8 is an enlarged view in front elevation illustrating the adjusting mechanism shown in Fig. 7.

The invention is illustrated in the drawings as embodied in a machine provided with a pair of wipers for overwiping the heel end portion of a shoe upper mounted on a last supported in the machine and the wipers are provided respectively with drivers which are power operated to drive a plurality of tacks through the overlasted materials and through the margin of an insole on the last bottom to secure the overlasted materials in lasted position. In their retracted position the wipers are spaced apart from each other to an extent somewhat greater than the width of the heel end portion of the shoe in order to provide clearance for the operation of mechanism for upwiping and stretching the back line

50 portion of the upper and for the operation of mechanism for automatically inserting a counter into the heel end portion of an upper supported in the machine independently of its last by the back line wiping and stretching instrumentalities. Inasmuch as the back line wiping and

55 stretching mechanism and the counter inserting means do not incorporate features of the present invention they are not illustrated in the drawings. In the operation of the illustrated organization the lasting wipers advance in unison from their position in Fig. 1 toward the heel end portion of a shoe in the machine and concomitantly move widthwise of the shoe toward each other into their

60 portion of the upper and for the operation of mechanism for automatically inserting a counter into the heel end portion of an upper supported in the machine independently of its last by the back line wiping and stretching instrumentalities. Inasmuch as the back line wiping and

65 stretching mechanism and the counter inserting means do not incorporate features of the present invention they are not illustrated in the drawings. In the operation of the illustrated organization the lasting wipers advance in unison from their position in Fig. 1 toward the heel end portion of a shoe in the machine and concomitantly move widthwise of the shoe toward each other into their

70 portion of the upper and for the operation of mechanism for automatically inserting a counter into the heel end portion of an upper supported in the machine independently of its last by the back line wiping and stretching instrumentalities. Inasmuch as the back line wiping and

relative position illustrated in Fig. 4 in which the wipers are mutually articulated for relative angular movement from their position in Fig. 4 into their position illustrated in Fig. 5 thereby to wipe the lasting margin of the heel end portion of a shoe upper over an insole on a last bottom. While the lasting wipers remain in their overwiped position shown in Fig. 5, the tack drivers are operated simultaneously to drive a plurality of tacks to secure the overlasted materials to the insole.

In their general organization and in many of their details of construction the wiper and tacker units are substantially similar to the wiper and tacker units illustrated and described in United States Letters Patent No. 1,852,015, granted April 5, 1932, on an application filed in the name of Jacob C. Jorgensen, to which patent reference may be had for a detailed description of those features of the wiper and tacker units not fully described herein.

Referring to Fig. 1 the illustrated wiper and tacker units are identified by the numerals 10 and 12. The wiper unit 12 at the right side of the machine has a discoidal extension 14 which registers with a complementally shaped recess in the wiper unit 10 when the wipers are brought into their mutually articulated position shown in Fig. 4 and the center of the discoidal extension 14 defines the axis of the relative angular movement of the wiper units in the overwiping operation. The wiper units are mounted respectively on a pair of carriers 16 and 18. The illustrated wiper carriers are of irregular elongate shape and are arranged to extend from front to back of the illustrated machine. At its rear end the wiper carrier 18 is pivotally mounted on a cylindrical boss 22 (Fig. 3) projecting upwardly from the right end portion of a crosshead 24. The wiper carrier 16 is pivotally mounted on a similar boss (not shown) projecting upwardly from the left end portion of the crosshead. The upper end of the boss 22 and the upper end of the corresponding boss at the left end portion of the crosshead together provide a means for supporting a horizontal cylinder 28 (Fig. 1) having ears 30 projecting laterally from its lower portion and arranged to rest upon the upper ends of the bosses. The ears 30 are secured to the upper ends of the bosses by headed screws 32 and 34. The forward portions of the wiper carriers 16 and 18 are supported by a flat horizontal rail 35 which forms a part of the machine frame. At their forward ends the wiper carriers overlie two plates 38 and 40 mounted respectively on two vertical posts 42 and 44 forming part of the structure of the machine frame, the plates being rigidly secured to the posts by tapered pins 46 and 48 (Fig. 2) extending through hubs 50 and 52 projecting downwardly from the plates. The paths of movement of the forward end portions of the wiper carriers 16 and 18 are determined by angular grooves 54 and 56 (Fig. 1) formed in the plates 38 and 40, respectively. Mounted in the grooves are rolls 58 and 60 carried, respectively, by ears 62 and 64 projecting outwardly from the forward end portions of the wiper carriers, respectively. During the first part of the forward movement of the wiper carriers the rolls 58 and 60 move toward each other in forwardly converging portions of the grooves 54 and 56 to advance the wiper units forwardly and inwardly into their articulated position shown in Fig. 4. During the remainder of the forward movement of the wiper carriers the rolls 58 and 60 traverse parallel forward portions of the grooves 54 and 56 and thus maintain the wiper units in their mutually articulated position as the wipers advance from their position of Fig. 4 to their position in Fig. 5 to perform the overwiping operation. During their overwiping movements the wiper units are held against upward movement by a fixed holdown plate 66. Referring to Fig. 2, the holdown plate 66 has two upwardly extending bosses 68 at its opposite ends, the bosses being bored for mounting on the posts 42 and 44 to which they are secured by pins 69. As shown in

Fig. 5, the holdown plate 66 is arcuate in shape and has at its opposite ends inwardly extending ears 71 which engage the forward portions of the wiper assemblies in their advanced positions shown in Fig. 5. As shown in Figs. 1 and 6, the holdown plate 66 is constructed and arranged to engage upper surfaces of brackets 70 and 74 secured to the wiper carriers 16 and 18, respectively. The brackets are secured to the wiper carriers by headed screws one of which is identified in Fig. 6 by the numeral 72. As shown in Fig. 1, the two brackets 70 and 74 are each in the form of an arc struck from the axis of angular movement of the wiper units. For mounting the wipers 10 and 12 on the wiper carriers 16 and 18 for arcuate overwiping movements about a common axis of articulation upper and lower ball-bearing assemblies are provided. The upper ball-bearing assembly for the wiper 10 is illustrated in Fig. 4 and comprises an arcuate race plate 76 having formed therein matrices mounting a plurality of balls one of which is identified by the numeral 78. As shown in Fig. 6, the balls 78 travel in an arcuate raceway in the form of a V-groove 79 in the bottom surface of the bracket 70 and engage an arcuate shoulder formed in an outwardly extending flange 80 of the wiper 10 and having a concave contour complementary to the curvature of the balls. The lower ball-bearing assembly for the wiper 10 comprises an arcuate race plate 82 which carries two sets of balls 84 and 86. The balls 84 travel in an arcuate V-groove 88 formed in the upper surface of the wiper carrier 16 and engage the wiper 10 in an arcuate groove 90 which registers with the groove 88. Similarly, the balls 86 travel in an arcuate V-groove 92 in the wiper carrier 16 and engage the wiper in a V-groove 94 which registers with the groove 92. The mounting of the wiper 12 for arcuate movement relatively to the wiper carrier 18 is similar to the mounting of the wiper 10 and will be understood from the above description of the mounting of the wiper 10.

In the operation of the illustrated machine the wipers and the carriers are advanced bodily from their position in Fig. 1 to their position illustrated in Fig. 4 by the operation of a pressure-fluid-actuated piston 96 illustrated in Fig. 3 and the relative arcuate overwiping movements of the wipers from their position in Fig. 4 to their overwiped position illustrated in Fig. 5 are effected by the operation of a pressure-fluid-actuated piston 98. The piston 96 is mounted in a fixed cylinder 100. As shown in Figs. 2 and 3 the cylinder has outwardly extending supporting feet 102 through which extend headed screws 104, which attach the cylinder to the base portion of a bracket 106 which is secured to a horizontal rail 103 attached to vertical plates 110 forming portions of the machine frame. As shown in Fig. 3 the piston 96 has a piston rod 112 extending forwardly therefrom through a bore in the head of the cylinder and secured at its forward end to the center of the crosshead 24. As shown in Fig. 2 the crosshead is guided for forward and rearward movements by the opposite side walls 114 of the bracket 106 in which are formed channels which receive the opposite end portions of the crosshead. The piston 98 is mounted in the cylinder 28 which, as hereinbefore described, is fixed to the crosshead 24. A piston rod 116 extends forwardly from the piston 98 through the head of the cylinder 28 and has a crosshead 118 fixed to its forward end portion. The opposite ends of the crosshead 118 are connected to the wipers 10 and 12 respectively by connections comprising two links 120 (Fig. 1) pivotally mounted at their rear ends on opposite end portions of the crosshead 118 and at their forward ends on the inner end portions of two arms 122 projecting inwardly from the upper end portions of elongated hubs 123 (Fig. 3) fulcrumed on headed screws 124 fixed in outward extensions 125 (Fig. 1) of the wiper carriers 16 and 18. Referring to Fig. 5 a short arm 127 projecting inwardly from the lower portion of the hub 123 is pivotally connected at its free end to a link 126 which is

pivotedly connected at its forward end to a lug 128 projecting outwardly from the wiper 12. A similar organization connects the arms 122 at the left side of the machine to the wiper 10.

For assisting the movement of the wiper carriers 16 and 18 toward each other during their forward movement from their position illustrated in Fig. 1 to their position in Fig. 4, the illustrated machine is provided with a booster herein illustrated as an expansion spring 130 (Fig. 1) mounted on a rod 132 pivotally mounted at its left end on a lug 134 on the wiper carrier 16 and slidably mounted in a bore in an ear 136 projecting upwardly from the wiper carrier 18, the spring 130 being confined between the ear 136 and a head 138 fixed to the right end portion of the rod 132. It will be seen that the expansive force of the spring 130 urges the wiper carriers 16 and 18 toward each other and thus eases the action of the cam rolls 58 and 60.

Referring to Fig. 5 the overwiped position of the wipers 10 and 12 is accurately determined in accordance with the size and width of the shoe in the machine by the engagement of the forward edge faces of the wiper 10 with an abutment member herein illustrated as a bracket 140 projecting rearwardly and to the right from a member 142 mounted on a slide 144 for adjustive movement in the direction of the length of a shoe in the machine. The slide 144 is mounted in the forward portion of the groove 54 for similar adjustive movement. The adjustive movement of the member 142 relatively to the slide 144 is effected by turning a thumbscrew 146, and during such adjustive movement the member 142 is held against angular movement about the axis of the screw by a flange 150 (Fig. 8) projecting from the slide 144 and positioned in a rabbed portion of the bracket 140. The thumbscrew 146 is mounted in a threaded longitudinal bore in the slide 144 and the member 142 is held against endwise movement relatively to the thumbscrew between a flange 152 and the head of the thumbscrew. The thumbscrew is held in its adjusted position by a resilient detent 154 (Fig. 7) fixed to an upward extension 155 of the member 142 and having its free end arranged to engage the knurled peripheral surface of the head of the thumbscrew. The adjusted position of the member 142 is indicated by the registration of the bracket 140 with a scale in the form of a plate 156 secured to the slide 144 and having shoe sizes inscribed thereon. The slide 144 is adjusted in the groove 54 to determine the position of the bracket 140 in accordance with the widths of the shoe to be operated upon. Referring to Fig. 8 such adjustment of the slide is effected by the operation of a hand lever 158 fulcrumed on a headed screw 160 fixed in the plate 38. The hub 162 of the hand lever is extended upwardly and has an arm 164 projecting to the right as seen in Fig. 8 from the upper extremity of the hub. Referring to Fig. 1, the free end portion of the arm 164 is bifurcated for engagement with a pin 166 projecting upwardly from the slide 144. The adjusted position of the hand lever 158 is indicated in terms of shoe widths by the registration of the hand lever with a scale inscribed on the margin of a segmental ratchet plate 168 secured by screws 170 to the plate 138, and the hand lever is secured in adjusted position by a pawl 172 (Fig. 8) pivotally mounted between ears 174 projected downwardly from the hand lever and constructed and arranged to enter any one of a plurality of uniformly spaced notches in the ratchet plate 168, one of which is identified in Fig. 1 by the numeral 176. The pawl is disengaged from the ratchet plate by the operation of a hand lever 178 projecting outwardly therefrom beneath the hand lever 158.

In the operation of the machine in which the illustrated mechanism is incorporated, a closed shoe upper such as the upper 180 illustrated in Fig. 1 having a quarter lining 182 is presented to the machine without its last. The extremity of the heel portion of the upper is inserted between the jaws of a back lining wiper as

sembly (not shown) and the top margin at the extremity of the heel portion of the upper is inserted between the jaws of a back line gripper (not shown). The back line wiper jaws are mounted on an arm which operates in the space between the wipers 10 and 12 with the wipers in their separated position shown in Fig. 1. While the top margin at the heel end of the upper is held by the back line gripper jaws the back line wiper jaws move upwardly to upwipe the back line portion of the upper from the top margin to the lasting margin and then grip the upper to hold it in position while a cement coated flanged counter such, for example, as the counter 184 illustrated in Fig. 1 is automatically inserted into the upper between the outer portion 180 and the lining 182. Thereupon lining wipers (not shown) are operated to upwipe the lining and bring it into intimate contact with the inner surface of the counter. A last having an insole attached to its bottom surface is then inserted into the supported upper. The upper is then drawn or tensioned towardly by breast line grippers (not shown) and pads (not shown) are brought into engagement with the heel end portion of the upper to clamp it against the last in the position in which it is located by the breast line grippers. The back line wiper jaws are then disengaged from the upper and moved upwardly into a position remote from the shoe to provide clearance for the operation of the heel end wipers 10 and 12. The piston 96 (Fig. 3) is then moved forwardly by pressure fluid transmitted through a flexible tube 186 communicating with a head 188 at the rear end of the cylinder 160, thereby advancing the wipers from their position in Fig. 1 to their position illustrated in Fig. 4. At this point in the operating cycle the advancement of the piston 98 is initiated by pressure fluid conducted to the cylinder 28 through a flexible tube 190 which communicates with a head 192 at the rear end of the cylinder 28. While the piston 98 advances to impart relative angular movement to the wipers 10 and 12 to cause them to overwipe the opposite side portions of the heel end of the upper, the piston 96 completes its advancement to cause the wipers to wipe the lasting margin at the back line portion of the upper inwardly over the insole on the last bottom. Upon completion of the operation of the wipers a plurality of tack drivers (not shown) incorporated in the wiper units are operated concomitantly to drive a plurality of tacks through the overlasted margin of the upper and the underlying portions of the counter, lining, and insole to secure the shoe parts in lasted position. Thereupon pressure fluid conducted to the forward portion of the cylinder 28 through a flexible tube 194 imparts rearward movement to the piston 98 to effect outward angular movement of the wipers, the fluid in the rear portion of the cylinder 28 being exhausted through the tube 190. Concomitantly rearward movement is imparted to the piston 96 by pressure fluid conducted to the forward portion of the cylinder 100 through a flexible tube 196, thereby returning the wipers to their position illustrated in Fig. 1, the fluid in the rear portion of the cylinder 100 being exhausted through the tube 186. The machine then comes to rest and the shoe is removed.

Having thus described our invention, what we claim as new and desire to secure by Letters Patent of the United States is:

1. In a machine for lasting an end portion of a shoe upper, a pair of end lasting wipers, a first piston, means operated by the first piston for imparting advancing movements of translation to the wipers, means for guiding the advancing movements of translation of the wipers in convergent paths, a second piston, and means operated by the second piston for imparting to the wipers angular movement relatively to each other.
2. In a machine for lasting an end portion of a shoe upper, a pair of end lasting wipers, a pair of carriers for the wipers respectively, a first piston, a second piston, means operated by the first piston for advancing the carriers and the second piston, and means operated by the

second piston for advancing the wipers relatively to the carriers.

3. In a machine for lasting an end portion of a shoe upper, a pair of end lasting wipers, a pair of carriers mounting the wipers respectively for angular movement relatively to the carriers, a first piston, means operated by the first piston for advancing the carriers, a second piston, and means operated by the second piston for imparting to the wipers angular movement relatively to the carriers.

4. In a machine for lasting an end portion of a shoe upper, a pair of end lasting wipers, a pair of carriers for the wipers respectively, a first piston, means operated by the first piston for advancing the carriers, a second piston, a cylinder in which the second piston is mounted, means whereby the first piston imparts a movement of translation to the cylinder, and means operated by the second piston for advancing the wipers relatively to the carriers.

5. In a machine for lasting an end portion of a shoe upper, a pair of end lasting wipers, a pair of carriers for the wipers, respectively, a member on which the carriers are mounted, a cylinder mounted on the member for movement with the carriers, a first piston for imparting a movement of translation to the member, a second piston mounted in the cylinder, and means whereby the second piston advances the wipers relatively to the carriers.

6. In a machine for lasting an end portion of a shoe upper, a pair of end lasting wipers, a pair of carriers for the wipers, respectively, a member on which the carriers are mounted for movement therewith, a cylinder mounted on the member for movement therewith, a first pressure fluid operated piston for imparting a movement of translation to the member, a second pressure fluid operated piston mounted in the cylinder, and means whereby the second pressure fluid operated piston advances the wipers relatively to the carriers.

7. In a machine for lasting an end portion of a shoe upper, a pair of end lasting wipers, a first piston for imparting movements of translation to the wipers, means for directing the movements of translation of the wipers in paths extending widthwise of a shoe in the machine to and from a position in which they are mutually articulated for angular movement relatively to each other, a second piston, and means operated by the second piston for imparting angular movement to the wipers.

8. In a machine for lasting an end portion of a shoe upper, a pair of end lasting wipers, a first piston for imparting movements of translation to the wipers, means for directing a first part of the movements of translation of the wipers in paths extending widthwise of a shoe in the machine thereby to advance the wipers; from a position in which they are separated from each other into a position in which they are mutually articulated for angular movement, and means for directing a second part of the movements of translation of the wipers in a path extending lengthwise only of the shoe thereby to advance the wipers after they have been brought into articulated position in order to wipe the extremity of a shoe upper over an insole on a last bottom, a second piston, and means operated by the second piston for imparting closing movement to the wipers thereby to complete the lasting operation.

9. In a machine for lasting an end portion of a shoe upper, a pair of end lasting wipers, a first piston for imparting movements of translation to the wipers, means for directing such movements of the wipers in paths extending widthwise of a shoe in the machine from a position in which they are separated from each other by a distance greater than the width of an end portion of a shoe in the machine into a position in which they are mutually articulated, a second piston, and means operated by the second piston for imparting wiping movements to the wipers.

10. In a machine for lasting an end portion of a shoe upper, end lasting wipers, a slide, connections from the

slide to the wipers, means for actuating the slide to advance the wipers from a position in which they are separated from each other into a position in which they are abutted to each other for relative angular movement, a cylinder mounted on the slide, a piston in the cylinder, and connections from the piston to the wipers, respectively, whereby the advancement of the piston in the cylinder imparts relative angular wiping movements to the wipers.

10 11. In a machine for lasting an end portion of a shoe upper, end lasting wipers, carriers for the wipers, respectively, a first piston, means operated by the first piston for actuating the carriers thereby to advance the wipers from a position in which they are separated from each other into a position in which they are mutually articulated for wiping movement, a second piston, and means operated by the second piston for moving the wipers relatively to the carriers and relatively to each other thereby to impart wiping movements to the wipers.

15 12. In a machine for lasting an end portion of a shoe upper, a pair of end lasting wipers, a pair of carriers for the wipers, respectively, a first piston, means operated by the first piston for actuating the carriers thereby to advance the wipers from a position in which they are separated from each other into a position in which they are mutually articulated for wiping movement, a booster for assisting the first piston, a second piston, and means operated by the second piston for imparting wiping movements to the wipers.

20 13. In a machine for lasting an end portion of a shoe upper, a pair of end lasting wipers, a pair of carriers for the wipers, respectively, and pressure fluid operated means for actuating the carriers thereby to advance the wipers from a position in which they are separated from each other into a position in which they are mutually articulated, and for imparting to the wipers angular movement relatively to each other and relatively to the carriers.

25 14. In a machine for lasting an end portion of a shoe upper, a pair of end lasting wipers, a pair of carriers for the wipers, respectively, and pressure fluid operated means for actuating the carriers thereby to advance the wipers from a position in which they are separated from each other into a position in which they are mutually articulated and for imparting to the wipers angular movement relatively to each other and relatively to the carriers, and a booster for assisting the pressure fluid operated means in the actuation of the carriers.

30 15. In a machine for lasting an end portion of a shoe upper, a pair of end lasting wipers, a pair of carriers on which the wipers are respectively mounted for arcuate movement relatively to the carriers, a first piston, means operated by the first piston for advancing each wiper and carrier assembly as a unit, a second piston, and means operated by the second piston for imparting to the wipers arcuate movements relatively to each other and relatively to the carriers.

35 16. In a machine for lasting an end portion of a shoe upper, a lasting wiper, a carrier on which the wiper is mounted for angular movement relatively to the carrier, a piston mounted for movement in the direction of the length of a shoe in the machine, means mounting one part of the carrier for movement with the piston, and means mounting another part of the carrier for movement in a path lying at an acute angle to the longitudinal median line of a shoe in the machine.

40 17. In a machine for lasting an end portion of a shoe upper, an end lasting wiper, a carrier on which the wiper is mounted for relative angular movement, a piston, operating connections between the piston and one part of the carrier, a fixed support for another part of the carrier, and means for determining the path of movement of the carrier relatively to the support.

45 18. In a machine for lasting an end portion of a shoe upper, an end lasting wiper, a carrier on which the wiper is mounted for relative angular movement, a piston, oper-

ating connections between the piston and one part of the carrier, a fixed support for another part of the carrier, means for determining the path of movement of the carrier relatively to the support, and a holdown constructed and arranged to hold the assembly comprising the wiper and the carrier against movement in one direction heightwise of a shoe in the machine.

19. In a machine for lasting an end portion of a shoe upper, a pair of end lasting wipers, a pair of carriers on which the wipers are respectively mounted for movement relatively to the carriers, an actuator on which the carriers are pivotally mounted, two members for guiding the carriers respectively, a holdown plate fixed relatively to the guiding members and constructed and arranged to hold the wiper and carrier assemblies against movement in one direction heightwise of a shoe in the machine, and means for moving the wipers relatively to the carriers thereby to cause the wipers to perform an overwiping operation on a shoe in the machine.

20. In a machine for lasting an end portion of a shoe upper, an end lasting wiper, a carrier on which the wiper is mounted for angular movement relatively to the carrier, a member mounting one portion of the carrier for movement in a rectilinear path extending toward and from one end of a shoe in the machine, a fixed member constructed and arranged to mount another portion of the carrier, means for determining the path of movement of the carrier relatively to the fixed member, and means for imparting to the wiper angular movement relatively to the carrier.

21. In a machine for lasting an end portion of a shoe upper, a pair of end lasting wipers, a first piston, means operated by the first piston for advancing the wipers bodily, a second piston, means operated by the second piston for imparting angular movement to the wipers, an

abutment member for determining the extent of the angular movement of the wipers, and means for adjusting the abutment member lengthwise of a shoe in the machine.

5 22. In a machine for lasting an end portion of a shoe upper, a pair of end lasting wipers, a pair of wiper carriers, a first piston, means operated by the first piston for advancing the wiper carriers, a second piston, means operated by the second piston for moving the wipers relatively to the carriers, and an abutment member constructed and arranged to limit the movement of the wipers relatively to the carriers.

15 23. In a machine for lasting an end portion of a shoe upper, a pair of end lasting wipers, a pair of carriers for the wipers, respectively, pressure fluid operated means for imparting to the wipers angular movement relatively to each other and relatively to the carriers, an abutment member for limiting the extent of movement of the wipers relatively to the carriers, a slide on which the abutment member is mounted, means for adjusting the slide lengthwise of a shoe in the machine, and means for adjusting the abutment member lengthwise of the shoe relatively to the slide.
